UNITED STATES PATENT OFFICE.

ELIHU THOMSON, OF LYNN, MASSACHUSETTS, ASSIGNOR TO THE THOMSON-
HOUSTON ELECTRIC COMPANY, OF CONNECTICUT.

ELECTRIC-ARC LAMP.

SPECIFICATION forming part of Letters Patent No. 297,197, dated April 22, 1884.

Application filed January 5, 1884. (No model.)

To all whom it may concern:

Be it known that I, ELIHU THOMSON, a citizen of the United States, and a resident of Lynn, in the county of Essex and State of Massachusetts, have invented certain new and useful Improvements in Electric-Arc Lamps, of which the following is a specification.

The object of my invention is generally to improve and simplify the construction and operation of electric-arc lamps.

My invention relates more especially to electric-arc lamps of such construction that the control of the carbons is effected by the action only of a derived-circuit magnet of high resistance acting in opposition to a suitable retractor.

My invention consists in providing a resistance in a branch around the carbons, and preferably of an amount greater than the arc, the function of which resistance is, at starting of the lamp, to force an abnormal amount of current into the high-resistance derived circuit, which abnormal current is effective in bringing the feed-regulating mechanism into normal or proper position for producing a feed of the carbon. Immediately thereafter the resistance branch is broken automatically, either by the movement of the feed-regulating mechanism or supporting-lever therefor, or by the actual establishment of the circuit through the carbons, and is kept broken so long as the lamp is in action. When the lamp ceases to act or the current ceases to flow, the resistance branch is established, either automatically or by hand, ready for the next operation. The device for breaking the resistance branch may be a circuit controller or switch of any desired construction, and is so constructed or arranged as to maintain the circuit of the branch while the feed-regulating mechanism is moving from its extreme retracted position to a normal or carbon-releasing position, or until the circuit is established in the carbons, when it is automatically released, either by mechanical or electrical means, and opens the branch, so as to leave the circuits of the lamp in their ordinary condition, and to thus permit the regulation or control of the carbons to proceed by the action of the current in the ordinary high-resistance derived circuit acting in opposition to a suitable spring or other retractor.

In carrying out my invention I may use any form or construction of regulating mechanism. In the present case I have shown and described a clutch or clamp; but I do not limit myself to such device, and may employ a gear-train or other mechanism. The magnet system and controlling-lever are so arranged or combined that when the retractor of the controlling-lever prevails over the effects of the current in the regulating derived circuit the carbons will be raised or separated, while if the magnet or other device in the derived circuit prevails the regulating mechanism will be moved against the influence of the retractor and a feed of the carbon permitted. When the arc is normal, the forces are balanced and the mechanism is at rest.

My invention provides a means of bringing the lamp into action by causing at the start an abnormal or increased flow of current in the high-resistance derived circuit, so that the lamp mechanism may be brought into proper position for starting the lamp or permitting the carbons to come together. Such abnormal flow is caused by the resistance branch around the carbons at the start, and is lessened or restored to normal amount by the breaking of the branch. When this occurs, the retractor for the regulating mechanism acts and separates the carbons, so as to form the arc, and the operation then goes on under the joint control of said retractor and of the current forced into the regulating high-resistance derived circuit by the arc resistance. The means in such high-resistance derived circuit for starting the lamp is preferably the regulating-magnet; but I do not limit myself in this respect, since the gist of the invention consists in starting the lamp by the abnormal flow of current in said circuit produced by the resistance around the carbons at starting.

Some of the many ways in which my invention may be carried into effect are shown in the accompanying drawings, in which—

Figure 1 is an elevation of a lamp embodying my invention. Fig. 2 illustrates a modification. Fig. 3 shows another form of circuit controller or switch that may be used for breaking the starting resistance branch automatically. Fig. 4 shows the form of feed-regulating magnet which I prefer to employ.

Referring to Fig. 1, R indicates the ordinary carbon-holder for the upper or positive carbon of an electric-arc lamp, and E E', respectively, the positive and negative carbons.

5 L indicates a feed-regulating lever, pivoted at p and acted upon by the opposing influences of a retractor, S, and of current flowing in a high-resistance derived circuit around the carbons. The influence of such current is brought to bear in the present case, in the ordinary way, by means of a high-resistance magnet, K, whose coils are in the ordinary high-resistance shunt around the carbons indicated by the numeral 5, which magnet acts upon a core or armature connected to L.

15 P is the pole of the magnet, and B a perforated armature attached to L, and embracing the conoidal or paraboloidal pole P. This form is adopted in order that the magnet may 20 exert the same pull upon the lever L in all positions of the armature for the same strength of current.

25 The magnet K is preferably a horseshoe-magnet, as indicated in Fig. 4. It is, however, to be understood that my invention is 30 not limited to any particular form or construction of the magnet system.

35 Lever L is the feed regulating or controlling lever of the lamp, and serves to adjust the position of the carbons by acting directly or indirectly upon any suitable devices that will, when moving in one direction, raise the upper carbon, and when moved in the opposite direction to a certain extent will permit the 40 carbon to feed or approach the opposite carbon. As typical of such devices, I have herein shown a clamp or clutch connected with lever L by a link, D, so as to be raised or lowered by said lever, or held stationary, according to 45 the relative strength of the current in the high-resistance-regulating circuit 5 and the strength of the retractor for the lever. Any other devices may be used in place of the clutch, provided they be of proper construction to cause 50 a release of the carbon when moved in one direction, and to lift the carbon when moved in the opposite direction. The clutch here shown is of the form heretofore invented by me, and 55 consisting, briefly speaking, of a clamp body or guide, C, through which the carbon or carbon-carrier may move, a dog or toe, d, pivoted on said body, and held normally in engagement with the carbon or carrier by means of a spring, Z, applied to an arm extending from 60 the toe, so as to prevent the carbon from moving downward through the clutch, and a stop, F, with which the arm engages to release the toe and permit the carbon to feed down whenever the clamp is lowered to a sufficient extent by the regulating-lever or other device, L.

65 W indicates the artificial or starting resistance of my invention, which is placed in a branch, 7, around the carbons at the starting of the lamp, and whose office is to force an 70 normal current into the derived-circuit branch 5, so that the magnet K or other device in said branch may act upon the lever L or other por-

tion of the feed-regulating mechanism in such way as to lower the clutch or clamp into the position where it will produce a feed of the carbon. 75 The resistance W is preferably greater than that of the normal arc, and its circuit is closed at the start through the contacts Q of a suitable switch or circuit-controller, N, carrying an armature, T, for an electro-magnet, V, and 80 provided with a retractor, S', that opens the switch when magnet V loses its power. In the arrangement here shown the contacts Q have to be closed by hand by an attendant at the moment the current begins to flow, after which they are kept closed by means of the electro-magnet V, whose coils are in the circuit 7 with W, and whose armature is attached to the controller N, while the feed-regulating mechanism is being lowered by means 85 of the lever L, under the action of the current forced into the circuit 5 and the coils of K. While current flows in the carbon circuit magnet V is shunted and is powerless to hold the switch N against the force of its retractor S. 90

95 The operation is as follows: When no current is passing, the carbons are held apart by the action of spring S, which retracts the lever L to its extreme position. When the current is turned on, it finds two paths—one through 5 and coils of K, and the other through W, magnet V, and contacts Q, which have been at the time closed by hand or other means. The resistance W forces currents into K to an abnormal amount, and the latter pulls down the 100 lever against the force of the retractor S, the contacts Q in the meantime remaining closed by the attraction of V. When the lever is pulled down to the proper point, the carbon 105 E feeds down into contact with E', and thus shunts the current from V, so that the spring S' opens contacts Q, thus breaking the circuit of W. The circuits are now in their normal 110 relation, and the spring S acts to raise the clutch and the upper carbon until its force is balanced by the current forced into K by the lengthening arc. An arc of a determinate 115 length having been thus formed, the operation of the lamp continues in the obvious and well-known manner, an increase of arc resistance increasing the power of K, so that lever L will be operated and produce a feed of the carbon. 120

125 The arrangement shown in Fig. 2 provides a means entirely automatic in its character for opening and closing the resistance branch that starts the lamp. In this case the magnet V is placed in the circuit, with the carbons between the terminals X and Y, and the resistance W is in a branch closed through contacts Q automatically by the action of the retractor-spring for the switch N when current ceases 130 to flow in V. When, therefore, the lamp is out of action, contacts Q are closed, ready for the start. When current is turned on, the mechanism is operated as before to permit the carbons to come together, immediately upon which the circuit through V is established and the contacts Q are opened by the action of

said magnet on its armature T. Contacts Q are now kept open by V so long as the lamp continues to act and current flows through the carbons. When the arc is extinguished, the 5 spring S' comes into play and closes contacts Q, ready for the next operation.

Instead of the magnetic arrangements described for controlling the switch, other devices may be employed.

10 In Fig. 3 I have shown a device that may be used for this purpose and that is purely mechanical in its operation. It is arranged to be operated by the lever L directly, or by some part moving therewith. This arrangement is made the subject of claims in another application for patent filed by me January 5, 1884, No. 116,513, and in which I have also shown other circuit-closing devices that may be employed in place of those shown in this 15 case. In this instance contacts Q are closed by means of an insulated catch, M, on the lever L, which catch engages with lever N when L is retracted to its extreme position, owing to the withdrawal of current from the line. 20 25 The circuit 7 is thus established, and when current is turned on produces, as before, an abnormal flow of current in K and a lowering of the clamp. In the forward movement of L in this operation, the catch M remains engaged with N, thus keeping the contacts Q closed until by the movement of the end of N inward on the arc of a circle the engaging parts are released, whereupon the circuit 7 is 30 opened, and the switch N is thrown back by its retractor out of range of the catch M and the contact carried thereby in the normal or usual movement of L in controlling the position of the carbons. The disengagement of the parts and the opening of the contacts are 35 40 45 50 suitably timed to take place when lever L and the feed mechanism have been lowered to such a point that the carbons may come together. A suitable stop controls the backward movement of the switch-lever N and retains it in such position that when the lever L is withdrawn to its extreme position by the action of its retractor S the catch M may again automatically engage with N, and at the same time close the starting-circuit 7, ready for the operation.

Many other modifications may be made in the form and disposition of the parts without departing from the invention.

In another application for patent filed by me January 4, 1884, No. 116,404, I have broadly claimed the combination, with the high-resistance magnet, of an artificial resistance around it for bringing the lamp into action; but the resistance in that case does not, as in this, form 55 60 a shunt to the carbons also.

What I claim as my invention is—

1. The combination, in an electric lamp, of feed mechanism, a derived-circuit magnet of high resistance regulating or controlling the 65 same, a resistance in a branch around the carbons closed at the start, and means for throwing said resistance out of circuit when the

lamp mechanism has been brought into operative position.

2. The combination, in an electric-arc lamp, 70 of a high-resistance derived-circuit magnet, feed mechanism controlled thereby, a resistance somewhat greater than the normal arc in a branch around the carbons for forcing current into the high-resistance derived circuit to 75 start the lamp, and a circuit-breaker for breaking the circuit of said resistance when the lamp mechanism has been brought into operative position, so as to leave the lamp to the controlling action of the derived-circuit magnet only. 80

3. The combination, in an electric lamp, of a high-resistance derived-circuit magnet, a retractor for the armature-lever thereof, feed-regulating mechanism controlled by said lever, a resistance somewhat greater than the normal arc in a branch around the carbons, and means for breaking said branch and keeping it broken when the current passes through the carbons, so that the lamp may continue in operation by the action of the derived-circuit 85 magnet only. 90

4. The combination, in an electric lamp whose carbon circuit is broken when the lamp is out of action, of a high-resistance derived-circuit magnet, feed mechanism controlled thereby, 95 a resistance in a branch around the carbons, and means for breaking said branch when the feed mechanism has been brought into normal or feed-regulating position, as and for the purpose described. 100

5. The combination, in an electric lamp, of a high-resistance derived circuit containing means for regulating the position of the carbons, a carbon circuit open when the lamp is out of action, a resistance in a branch around 105 the carbons, and a circuit-controller therefor actuated by a magnet in the carbon circuit, as and for the purpose described.

6. The combination, in an electric lamp, of a regulating-lever, L, a high-resistance or derived-circuit magnet, and a retractor acting upon said lever in opposite directions, feed-regulating mechanism that holds the carbons apart when the lever is retracted to an extreme position, a resistance in a branch around the 115 carbons, and means for breaking said branch and holding it broken when current flows through the carbons.

7. The combination, in an electric lamp whose carbons are separated at the start, of a high-resistance derived-circuit magnet, feed mechanism controlled thereby, and a resistance in a branch around the carbons for forcing current into the high-resistance magnet, so that it may have power to start the lamp. 120 125

8. An electric lamp constructed to have three conducting-paths—one through the carbons, one through the high-resistance-controlling magnet, and a third through a resistance greater than that of the arc—as and for the purposes 130 described.

9. The combination, in an electric lamp having a high-resistance derived circuit carrying the regulating-current, of a second branch

around the carbons containing a resistance
preferably greater than the normal arc, and
closed at starting of the lamp, and means for
bringing the lamp mechanism into operation,
5 placed in the high-resistance circuit and en-
ergized by the abnormal flow of current pro-
duced therein by the presence of the second
resistance branch.

Signed at Lynn, in the county of Essex and
State of Massachusetts, this 1st day of Jan-
uary, A. D. 1884.

ELIHU THOMSON.
